Inventor:
Leo Mayer

By Edwin F. Schwartzberg
Atty.

UNITED STATES PATENT OFFICE.

LEO MAYER, OF BOSTON, MASSACHUSETTS, ASSIGNOR TO HENRY COLE COMPANY, OF BOSTON, MASSACHUSETTS.

ELECTRICAL CONNECTER.

Application filed February 9, 1927. Serial No. 167,044.

This invention relates to electric connectors used in connecting electric conductors together, and has special application to electric connectors used with automobile lights.

5 The object of my invention is to provide simple and effective means for making and breaking the circuit.

10 Another object of my invention is to provide a simple and effective means for making and breaking such a circuit and is applicable equally alike to electric lights having a one wire system, a two wire system, and to a system which is partly one wire and partly two wire system.

15 The invention will be hereinafter considered in detail and specifically claimed. Reference will now be had to the drawing forming a part of this application, wherein there is illustrated a preferred embodiment of my 20 invention, but it is understood that the elements thereof can be varied or changed as for shape, size, or form without departing from the spirit of the invention.

Fig. 1 is a sectional view of a two wire 25 electric system embodying my invention.

Fig. 2 is a sectional view of an electric system which is partly one wire and partly two wire system, embodying my invention.

30 Fig. 3 is a sectional view of one wire electric system embodying my invention.

Fig. 4 is a view on line 4-4 of Fig. 1.

Fig. 5 is a view on line 5-5 of Fig. 2.

Fig. 6 is a view on line 6-6 of Fig. 3.

35 Fig. 7 is a view on line 4-4 of Fig. 1 showing the position of the switch and wire when electric contact is made.

In my drawings, referring to Fig. 1:

10 represents an incandescent light or bulb mounted in the shell 11 which is provided 40 with bayonet slot 12 to receive the stud 13 or the bulb. The shank of the lamp is provided at its inner end with two contacts 14 and 15. These two contacts make electrical contact with the ends of the spring pressed 45 plungers 16 and 17, of a well known construction. The rods 18 and 19 have extensions 20 and 21 which are connected to the lead wires. The rod 18 is divided into two parts 22 and 23.

50 The shell 24 has an opening 25 therein through which the handle 26, which is made of nonconducting material, passes. The shell

24 is provided with extensions 27 and 28, which have openings 29 and 30. The handle 26 is pivotally connected to the shell by 55 means of pin 31. The head of the handle is provided with a cam like arrangement 33 as shown in Fig. 4 and Fig. 7, the operation of which will presently be explained.

One end of a resilient piece of metal ribbon 32 is firmly connected to the shell and the other end is free. Under normal conditions the free end of the ribbon 32 is out of contact with the rods 22 and 23 and therefore the electric circuit is broken. When it 65 is desired to make the electric circuit the handle 26 is rotated counter clockwise. The cam 33 comes in contact with the ribbon 32 and moves the ribbon so that it makes contact with the rods 18 and 19 and the circuit is thereby established. To break the 70 circuit the handle 26 is moved in the opposite direction and the resiliency of the ribbon forces it away from the rod and the circuit is broken.

75 The cam mechanism used to make and break the circuit described above is used also for making and breaking the electric circuit shown in Figs. 2 and 3. In Fig. 2 the ribbon 32 is moved so as to make contact 80 with rod 34. In Fig. 3 where one wire electric system is shown, the circuit is made and broken on the rod 35.

From the above description it will be seen that I use a simple and positive means to 85 make the electric circuit. To break the circuit, the resiliency of the metal is used.

Having described my invention, what I claim is:

In an electrical lamp receptacle, the combination of a tubular shell, a base member located in one end of said shell, a vertically located contact member longitudinally located with respect to said shell and located in said base member at one side thereof, a second contact member located in said base member on the opposite side thereof, the longitudinal axis of which is obliquely disposed with respect to the longitudinal axis of said shell, a switch member pivotally mounted in the side of said shell and operatively disposed at ninety degrees to the vertical axis of said vertical contact member, a spring contact member transversely dis-

posed to said shell and attached at one end thereof by passing said end through said shell at two points, said end at the first point passing outward and, at the second point 5 passing inward after which the remaining end is bent outward against the inner wall of said shell, the opposite end of said spring

contact member adapted to be pressed into contact with said vertical contact member by means of a cam surface located on the inner portion of said switch member, substantially as shown and described.

LEO MAYER.
